UNITED STATES PATENT OFFICE.

MORGAN A. GREEN, OF PAYETTE, IDAHO.

SHEET-PILING GUARD.

1,070,886.

Specification of Letters Patent. Patented Aug. 19, 1913.

Application filed January 8, 1913. Serial No. 740,864.

To all whom it may concern:

Be it known that I, MORGAN A. GREEN, a citizen of the United States, residing at Payette, in the county of Canyon and State 5 of Idaho, have invented new and useful Improvements in Sheet-Piling Guards, of which the following is a specification.

This invention provides a novel form of protective means for use in the construction 10 of coffer-dams, caissons, cement walls and the like in structural work requiring the damming or shutting out of water from excavations or other nature of work.

The invention consists essentially of a reinforced wall embodying wooden piles and metal beams arranged in alternation, the metal beams interlocking with the wooden piles or timbers to form a substantial wall.

The invention consists of the novel features, details of construction and combination of parts, which hereinafter will be more particularly set forth, illustrated in the accompanying drawing, and pointed out in the appended claims.

25 Referring to the drawing, forming a part of the specification, Figure 1 is a view in elevation of a composite structure embodying the invention. Fig. 2 is a top view.

Corresponding and like parts are referred 30 to in the following description, and indicated in all the views of the drawing, by the same reference characters.

The inclosing or protective wall or structure comprises piles or beams 1 of wood and metal beams 2 intermediate of the beams 1 and interlocking therewith, the metal beams 2 being of I form, the outer flanges overlapping the outer faces of adjacent wooden beams and the body portion of such beams 40 2 coming between the wooden beams 1, as clearly indicated in Fig. 2. The wooden beams or piles 1 are of rectangular form and of a size so as to fit snugly between the flanges of the intermediate I beams 2. The 45 metal I beams by reason of their arrangement serve as ties and reinforcements for the wooden I beams 1 and to further strengthen the wall or structure stays 3 are located upon opposite sides of the beams 1 and 2 and may be secured thereto in any 50 manner. The stays 3 follow the outline of the wall or sheet piling.

From the foregoing description, taken in

connection with the accompanying drawing, the advantages of the construction and 55 of the method of operation will be readily apparent to those skilled in the art to which the invention appertains, and while I have described the principle of operation of the invention, together with the device which I 60 now consider to be the best embodiment thereof, I desire to have it understood that the device shown is merely illustrative, and that such changes may be made when desired as are within the scope of the claims 65 appended hereto.

The metal I beams are sharpened at their lower ends by having opposite sides beveled, the edges extending at a right angle to the length of the structure. The 70 lower ends of the piles are similarly sharpened, the edges extending lengthwise of the structure. When driving the piles and I beams their upper ends are protected by means of a cap, the latter being indicated 75 at 4 by the dotted lines in Fig. 1. This cap prevents upsetting of the ends of the beams and piles during the driving operation.

Having thus described the invention what is claimed as new, is:—

80 1. A protective wall or structure of the character described comprising wooden beams and I beams having an alternate arrangement, the flanges of the I beams embracing the outer sides of adjacent wooden beams.

2. An inclosing structure or protective wall of the character set forth comprising wooden beams of rectangular form in cross section and intermediate middle I beams, 90 the latter having their flanges embracing the outer sides of adjacent wooden beams.

3. An inclosing wall or protective structure of the character described comprising wooden beams and metal I beams alternately arranged with the flanges of the I beams embracing the outer sides of adjacent wooden beams, and stays extending along opposite sides of the wall or structure.

95 In testimony whereof I affix my signature 100 in presence of two witnesses.

MORGAN A. GREEN.
